US00D733240S

(12) **United States Design Patent**
Wilson et al.

(10) **Patent No.:** US D733,240 S
(45) **Date of Patent:** ** Jun. 30, 2015

- (54) **FLAT BOTTOM VEE ICE SKATE BLADE**
(71) Applicant: **1339513 Ontario Ltd.**, Harrow (CA)
(72) Inventors: **Murray David Wilson**, Harrow (CA);
Steven David Wilson, Harrow (CA);
Omer Leon Hageniers, Windsor (CA)
(73) Assignee: **1339513 Ontario Ltd.**, Ontario (CA)
(**) Term: **14 Years**
(21) Appl. No.: **29/464,463**
(22) Filed: **Aug. 16, 2013**

Related U.S. Application Data

- (63) Continuation of application No. 29/388,321, filed on Mar. 28, 2011, now Pat. No. Des. 688,343, which is a continuation-in-part of application No. 29/333,603, filed on Mar. 12, 2009, now Pat. No. Des. 637,676, and a continuation-in-part of application No. 12/402,838, filed on Mar. 12, 2009, now Pat. No. 8,056,907.

(57) **CLAIM**

The ornamental design for a flat bottom vee ice skate blade, as shown and described.

DESCRIPTION

FIG. 1 is a perspective view of a flat bottom vee ice skate blade.

FIG. 2 is an enlarged front side view of the ice skate blade of FIG. 1.

FIG. 3 is an enlarged rear side view of the ice skate blade of FIG. 1.

FIG. 4 is a reduced top view of the ice skate blade of FIG. 1.

FIG. 5 is a reduced bottom view of the ice skate blade of FIG. 1.

FIG. 6 is a right side view of the ice skate blade of FIG. 1.

FIG. 7 is a left side view of the ice skate blade of FIG. 1.

FIG. 8 is a greatly enlarged close-up of the front side of FIG. 2.

FIG. 9 is a cross-sectional view of the ice skate blade taken from line 9-9 of FIG. 2.

FIG. 10 is a perspective view of a flat bottom vee ice skate blade.

FIG. 11 is an enlarged front side view of the ice skate blade of FIG. 10.

FIG. 12 is an enlarged rear side view of the ice skate blade of FIG. 10.

FIG. 13 is a reduced top view of the ice skate blade of FIG. 10.

FIG. 14 is a reduced bottom view of the ice skate blade of FIG. 10.

FIG. 15 is a right side view of the ice skate blade of FIG. 10.

FIG. 16 is a left side view of the ice skate blade of FIG. 10; and,

FIG. 17 is a greatly enlarged close-up of the front side view of FIG. 11.

The broken line showing of portions of an ice skate is included for the purpose of illustrating environmental structure and forms no part of the claimed design.

1 Claim, 13 Drawing Sheets
